United States Patent Office

Des. 196,336
Patented Sept. 17, 1963

196,336

JAR

Richard R. Tuott, Coon Rapids, Minn., assignor to Carlson Engineered Products, Inc., Minneapolis, Minn., a corporation of Minnesota

Filed May 29, 1963, Ser. No. 75,113

Term of patent 14 years

(Cl. D58—25)

FIG. 1

FIG. 2

FIG. 3

FIG. 4

FIG. 1 is a front elevational view of a jar embodying my new design;

FIG. 2 is a side elevational view thereof;

FIG. 3 is a rear elevational view thereof; and

FIG. 4 is a top plan view thereof, the bottom being substantially plain.

I claim:

The ornamental design for a jar, as shown and described.
